UNITED STATES PATENT OFFICE.

JACOB M. LONDON, OF TUNNELTON, PENNSYLVANIA, ASSIGNOR, BY DIRECT AND MESNE ASSIGNMENTS, OF ONE-FOURTH TO GEORGE M. CRAWFORD AND ONE-HALF TO EMIL M. REFIOR, BOTH OF PITTSBURGH, PENNSYLVANIA.

EXCAVATING AND LOADING APPARATUS.

1,327,053.

Specification of Letters Patent.

Patented Jan. 6, 1920.

Original application filed July 25, 1917, Serial No. 182,658. Divided and this application filed March 7, 1918. Serial No. 220,925.

To all whom it may concern:

Be it known that I, JACOB M. LONDON, a citizen of the United States, and resident of Tunnelton, in the county of Indiana and 5 State of Pennsylvania, have invented a new and useful Improvement in Excavating and Loading Apparatus; and I do hereby declare the following to be a full, clear, and exact description thereof.

10 This invention relates to excavating and loading apparatus and more particularly to that type used in mines for removing dislodged coal and has for its primary object the arrangement of the parts in such a manner that gravity may be relied on to cause 15 the greatest bulk of the material to fall in a position to be readily conveyed to the rear of the machine.

Another object of the invention is to provide continuous operating feeders for moving the material to a point where it will be gathered by a system of conveyers, relying 20 on independent drive means for moving the feeders into engagement with the pile of coal.

25 A further object of the invention is the manner of mounting the feeders and drive mechanism therefor so that the feeders may be arranged at different angles with relation to the pile of coal.

30 Beside the above my invention is distinguished in the manner of driving and supporting the feeders so that the same may be quickly thrown to an operative or an inoperative position and when in the latter position the feeders will not interfere with the travel of the apparatus into and about the mine.

35 With these and other objects in view the invention will be better understood from the following detailed description taken in connection with the accompanying drawings wherein:

40 Figure 1 is a side elevation of the invention shown in combination with a suitable coal cutter.

45 Fig. 2 is a top plan view of the apparatus.

Fig. 3 is an end elevation of the device in combination with a coal cutter mechanism.

50 Fig. 4 is a front elevation illustrating the scoop and a portion of the conveyer.

Fig. 5 is a longitudinal sectional view of the device.

Figs. 6 and 7 are detail views of the saddle arrangement connecting the device to the 55 coal cutter.

Fig. 8 is a front elevation showing in dot and dash lines an inoperative position of the feeders.

Figs. 9 and 10 are detail views of the turn-table.

Fig. 11 is a detailed sectional view of the drive mechanism for the feeders.

My improved form of coal loading apparatus is connected to a frame "C" at a point 65 directly below the coal cutting mechanism "A" which may be constructed as illustrated in my copending application, Serial No. 182,658; filed July 25, 1917, of which this application is a division, but it will be understood that the subject matter of this application is not limited to use with the device described in my co-pending application, but may be used with other machines if desired. 70

The frame "C" is mounted upon a suitable form of wheel supported turn table "B" in such a manner that when acting in combination with other mechanism, hereinafter described, a pile of coal may be acted upon at 80 various angles and the same moved toward the rear of the apparatus.

A carriage 1 including a bearing 2, pivotally connected to a block 3 slidably mounted upon the frame "C," is automatically 85 moved in a manner now to be described.

Fixed to the carriage 1 is an electric motor or other suitable power device 4, the armature shaft 5 of which has one end associated with a pair of worms 6 and 7, the former driving the conveying means to be described later, and the latter coöperating with the gear 8 fixed upon the shaft 9 that has also fixed thereon sheave wheels 10 and 11 around which pass chains 12 directed 90 around idlers 13 and connected to the block 3. From this arrangement it will be seen that when the clutch 14, arranged in the shaft 9, is operated, movement will be transmitted through the chains 12 to the block 3 and as a result the carriage 1 and the conveying means, to be described later, will be moved toward or away from the pile of coal 100 depending upon the direction of rotation of the motor.

The remaining end of the armature shaft 105

The remaining end of the armature shaft

5 has a gear connection 15 with a pair of parallel shafts 16 and 17 each supporting a beveled gear 18. Associated with each of the beveled gears 18 is a coal feeder 19 consisting of an upper rake device 20 and a lower rake device 21 of different capacities, the upper having the larger capacity. Each rake device consists of a plurality of teeth or scrapers 22 carried on an endless belt or chain 23 driven in any suitable manner by the shaft 24 that receives its motion through a beveled gear 25 rigidly secured thereto and engaging the beveled gear 18.

The frame 26 of each of the feeders is 15 provided with a bearing 27 supported for rotation upon one of the heretofore mentioned parallel shafts so as to swing vertically in an arc of a circle, as shown in dot and dash lines in Fig. 8. For the purpose 20 of swinging the feeders to this position a cable 28 is provided for each feeder having one end connected directly to the feeders and trained around suitable idlers 29 and then passed over a drum 30 that has a clutch 25 connection with the shaft 9; thus it will be seen that the machine may be readily moved into and about in a mine and quickly arranged in an operative position.

At this point I wish to call attention to 30 the fact that by use of this swinging connection of the feeders by the cable 28, the wheel supported turn table "B," and the pivoted connection between the carriage 1 and the frame "C," the feeders may be arranged in 35 a plurality of positions so as to insure the proper coöperation of the feeders with the dislodged pile of coal.

This manner of acting upon a pile of coal 40 by the feeders causes the major portion of the coal to fall as the feeders only excavate a certain amount of coal from under the pile of coal and gravity is relied on for the major portion of the pile to gravitate upon the conveying means hereinafter described.

45 Arranged directly over the feeders are shields 31 for preventing the falling of the coal from interfering with the drive mechanism of the feeders. Working directly under the feeders is a scoop 32 that is carried 50 by the front end of the conveyer 33 and at this point I wish to call attention to the fact that the operation of the feeders and the location of the shields and of the scoop are such that the coal will be brought and 55 fall between the two sets of feeders and be caught by the conveyer 33 which has its end located at this point.

Conveyers 33 and 34 are pivotally supported at 35 upon the carriage 1 and are 60 adapted to receive and convey the dislodged coal to the rear of the machine. The conveyers 33 and 34 have a drive connection 36 with the worm 6. For the purpose of 65 illustration I have shown a system of conveyers "D," mounted on a truck 42 and ar-

ranged in the rear of the conveyer 34 for continuing the travel of the material. The truck 42 is connected to the truck 43 by any suitable means as chain 44.

If found advantageous in practice the 70 turn table "B" may be mechanically operated by the worm shaft 37 that engages the rack bar 38 secured to one of the disks of the turn table, and this worm shaft 37 is driven in any suitable manner as shown diagrammatically at 39, in Fig. 1 of the drawings. 75

To facilitate the travel of device about a mine the truck 43 may be provided with a motor 45 suitably geared thereto. Motor shaft 46 carries the sprocket 47 for driving 80 the worm shaft 37 by means of the chain 48 operating the sprocket 49 which has a clutch connection 50 with the worm shaft 37.

In Figs. 6 and 7 there is shown the saddle arrangement 51 which connects the frame 85 "C" to the coal cutter "A." This arrangement permits the rocking adjustment of the coal cutter upon the frame "C." Bolts 40 are provided for securing the coal cutter in the adjusted position. 90

To complete the invention I arrange at suitable points jacks 41 pivotally connected to the frame "C" and adjustably engaging the wall of the mine.

It is to be understood that while all of 95 the several features of my improved coal cutting and loading apparatus have special coöperation with one another and together constitute a particularly effective machine for the purpose in view, certain of these 100 features may be applied in other relations and I therefore desire to cover the combinations present in the several parts of my machine whether employed in the general organization shown or elsewhere. 105

It is further understood that the structural embodiment of the invention as a 110 whole and its various features as shown are merely illustrative and not restrictive since I am well aware that many of the details of construction can be widely varied without departing from the principle of the invention. I therefore do not desire to be limited in this construction or in any other except as set forth in the appended claims. 115

I claim—

1. In a coal loading apparatus, a carriage mounted for vertical and horizontal movements, and coal feeders swingingly connected to the carriage and each including an 120 upper and a lower rake device of different capacities.

2. In a coal loading apparatus, a carriage mounted for vertical and horizontal movements, coal feeders swingingly connected to the carriage, each including an upper and a lower rake device of different capacities, and means for swinging the feeders to an operative or inoperative position. 125

3. In a coal loading apparatus, a carriage 130

mounted for vertical and horizontal movements, coal feeders swingingly connected to the carriage, each including an upper and a lower rake device of different capacities, 5 means for swinging the feeders to an operative or inoperative position, and means for changing the active positions of the feeders.

4. Coal loading mechanism comprising a carriage mounted for vertical and rectilinear 10 ear movements, a conveyer supported thereby, driving mechanism mounted on the carriage and including drive shafts, a pair of feeders mounted for vertical swinging movements independent of each other upon the 15 drive shafts, said feeders being normally spaced the required distance apart for allowing the passage of the material onto said conveyer, and cables for swinging said feeders to an inoperative position.

20 5. A coal loading apparatus comprising a

frame, a sliding bearing mounted on said frame, a carriage pivotally mounted on said bearing, coal feeders swingingly connected to said carriage, and each including an upper and a lower rake device of different capacities. 25

6. A coal loading apparatus comprising a frame, a sliding bearing mounted on said frame, a carriage pivotally mounted on said bearing, coal feeders swingingly connected to said carriage, each including an upper and a lower rocking device of different capacities, and means for swinging said feeders to an operative or inoperative position. 30

In testimony whereof I, the said JACOB M. 35 LONDON, have hereunto set my hand.
